PACKING AND DISPLAY DEVICE

Abner B. Carey, Grayville, Ill.

Application March 25, 1935, Serial No. 12,860

2 Claims. (Cl. 226—16)

The object of my invention is to make a packing and display device, which finds particular application in the packing and display of eggs and fruit. It may be equally well employed in the 5 packing and displaying of any commodity, such as food products when packed, both in bulk and individually, in rows or layers, as is the case with the packing of eggs and fruit, such as oranges. Throughout this application the specific adaption 10 considered will be that of packing and displaying eggs, but it is understood that it can be equally used for the commodities indicated. Furthermore the description herein will be specifically dedicated to disclosing the packing and display 15 of eggs when they are packed, as is usually the case with the use of spacing elements and basal supports.

Eggs, being fragile, the loss through breakage in packing is appreciable. The cost of packing eggs 20 must be reduced to a minimum. In the packing operation, each egg must be handled separately. The conventional method is to place a flat plate or basal support made of cardboard or pressed composition material, in the bottom of the egg case. A basal support usually consists of an integral sheet of composition material, on which are 25 pressed projections. In the projections are formed cups or dished depressions. The cups are of such shape and size that an egg may be stood 30 on its end in each cup. On this basal support is placed the cardboard separators, which are collapsible, in such position that the cups of the basal support are positioned within the confines of the spaces formed between the spacing elements. An 35 egg positioned in the spacing element and on the basal element is supported by both. Over the top of the spacing element is placed one basal plate, which in turn on its upper side forms the support 40 for the next layer of eggs. This process is continued until the entire space within the egg case is filled with eggs.

In the conventional egg case there are five 45 layers of eggs, each layer comprising three dozen eggs. The case is divided into two portions, each holding a like number of eggs. It is obvious that in placing the eggs in the spacing elements, the eggs must not be permitted to fall from the hand, that is the eggs must be carefully and lightly positioned in the spacing elements. This operation is 50 performed by unskilled operators. In placing the eggs in the spacing elements of the bottom or lower layers, the percentage of breakage is great, because the operator must reach to the bottom of the case, or at least the lower portion of it with 55 the egg in his hand. There is practically no loss

through breakage in placing eggs in the separating element when the top or upper separating elements are filled. Applicant has devised means for reducing the breakage in packing of the lower layers to a point where it is not higher than is the 5 case in packing the upper layers. This is accomplished, in applicant's device, by filling one layer when its top is either flushed with the top of the egg case, or protrudes above the sides of the egg case. When the layer is filled, the layer is lowered 10 a distance equal to the height of a layer of eggs, and another spacing element is positioned on the filled spacing element, in the manner previously described. The second spacing element is then 15 filled, forming the second layer of eggs. In this manner by successfully lowering each layer, all of the layers will be filled without compelling the operator to stoop or reach into the egg case. The spacing element that is to be filled is always easily 20 accessible.

It is well known that the display of commodities, particularly fruit, increases the sale of the commodity. This is true with commodities, such as eggs, but they are seldom exhibited, because there is no practical means of making the display. It is desirable to make the display without 25 being compelled to remove the eggs. The preferable method of displaying the eggs is while the eggs are still in the case. But when they are in the case, only the extreme tops of the eggs are 30 visible, because the top layer of eggs is flushed with the sides of the case, within which the eggs are packed.

Applicant has devised a means for elevating the eggs in the case, so that the upper layer of eggs 35 will protrude above the sides of the case. The spacing elements may then be removed from the upper exposed layer of eggs, in which position they will be supported by the basal support, and in which position they are entirely visible, with the exception of the small portion in contact with the 40 cups in the basal support. As each layer of eggs is sold, the succeeding layer is elevated to the protruding position. If the eggs are to be subsequently packed in cartons for the consumer, the 45 separating elements are not removed from the case or from the upper protruding layer.

The device herein described is to be used by 50 retailers, who are dispensing eggs from the case, and who are subsequently confronted with the task of packing the eggs for the consumer in small 55 quantities, such as dozen lots. Most eggs that are sold by a retailer are removed from the case, and placed in a carton. In this carton, which is usually made of pasteboard, and which is folded from

a flat cut sheet, are positioned spacing elements of the same type as are used in the egg case, with the exception that the carton is of such size as to accommodate either one or two dozen eggs; whereas in each layer of eggs in the case, space is provided for three dozen eggs. Obviously where the eggs that are removed from the case are simply placed in a paper bag, the packing operation, from the standpoint of the retailer, cannot be simplified. He must handle each egg and perform the operation very carefully. With this situation, applicant is not concerned.

Applicant is concerned with the removal of the eggs from the case without removing them from the spacing elements, so as to use the spacing elements of the egg case, as the spacing element for the carton, thereby obviating the necessity of handling the eggs separately, and thereby saving the expense of duplication of the spacing elements. By applicant's method and device, the upper layer of eggs, together with the basal plate and the spacing elements, is elevated until the bottom of the basal plate and of the spacing elements is slightly elevated above the side walls of the egg case, and of the stand used by applicant in this device. The entire layer of eggs, together with the basal plate, and the spacing elements, is slid over the top of the next lower layer of eggs, and spacing elements over the lateral wall of the egg case, over the lateral wall of the stand, provided by applicant, on to a plate secured to the stand. On this plate, by the method to be subsequently described, one or two rows of eggs are cut away from the layer of eggs, and the row or rows that have been cut off are then slid into the conventional carton, which is held at the end of the plate.

It will, therefore, be seen that applicant completely removes the necessity of the purchase by the retailer of the carton spacing elements. Not only that, but he enables the retailer to remove the eggs from the case to the carton without contact with each egg, or with any of the eggs. This results in a great economy in operation, both as to time and as to breakage. The device, herein described, may be made of few and simple parts that lend themselves readily to multiple production. The device may be cheaply made, is portable, light in weight, and provides simultaneously storing space for the egg case, until the eggs are sold, and provides a novel display possibility.

In the handling of bulk commodities, such as, for instance, oranges or nuts or potatoes, it is well known that the uppermost portions of the containers and content are the most salable. No customer desires to purchase from a container that is nearly empty. He desires preferably to purchase from a container that has just been opened. Furthermore, in the case of the bulky storage, as the upper portions of the commodity are removed, it becomes very difficult for the purchaser to see the commodity near the bottom of the container. It is, therefore, to the advantage of the retailer to have the commodity always visible from the top, both from the standpoint of the optical appeal that it makes, and from the standpoint of conveying to the prospective purchaser, the impression that the container is not practically empty. Furthermore in the case of perishable fruit or vegetables, it is an advantage to have them aerated as much as possible, and the elevating process used in applicant's device succeeds in accomplishing this to a degree for all

of the fruit, and to a maximum degree for the upper practically totally exposed fruit.

With these and other objects in view, my invention has relation to certain novel features of construction and arrangement of parts, as will be hereinafter more fully described, pointed out in the claims and illustrated in the drawings, in which

Fig. 1 is a plan view of my device.

Fig. 2 is an end elevation of my device, showing the elevator removed from the device proper, except by its chain contact with the device proper.

Fig. 3 is a transverse sectional elevation taken on the line 3—3 of Fig. 1.

Fig. 4 is a longitudinal sectional elevation, and

Fig. 5 is a fragmental plan view of the plate used in my device, showing the method of cutting the spacing elements and positioning them in a carton.

Fig. 6 is a view similar to Fig. 3, showing a bulk commodity, such as oranges in place of eggs, as are shown in the other figures of the drawings.

Numeral 7 designates a stand having the four legs or posts 8 and the side walls 9 and the end walls 10. One of the side walls 9 extends almost to the bottom of the legs or posts 8. The end walls 10 extend almost to the bottom of the legs or posts 8. The walls 9 and 10 are secured to the legs or posts 8, by any conventional means, such as nails or screws. By this means is formed a stand rectangular in shape and slightly higher than twice the height of the case into which products are to be placed or removed. The walls 9 and 10 are of such length that the space within them will accommodate the egg case. These dimensions are such that the egg case will fit flushly within the stand 7, and against the walls 9 and 10. On the inner faces of the end walls 10 are secured the cleats 11, the ends of which are flush with the side walls 9. The cleats 11 are positioned a distance below the top of the stand 7, equal to the height of the case that is to be positioned within the stand 7. It will be seen that by the structure thus far described that an egg case, either empty or full, may be positioned within the stand 7, with its side and end walls flush with the side and end walls of the stand 7. One of the walls 9 is cut away as shown at 12.

The structure to be now described is that which is necessary to elevate or lower layers of eggs into and out of the case. It is to be understood that the egg case itself remains stationary. Numeral 13 designates a shaft, which is journaled in the end walls 10. The protruding ends of the shaft 13 that extend beyond the end walls 10 are squared for the reception of a handle 14. By means of the structure shown, the handle 14 may be used at either end of the shaft 13.

Numeral 15 designates a set screw for tightening the handle 14 on to the end of the shaft 13. Numeral 16 designates an elevator, which consists of a substantially U-shaped plate, having one of the parallel faces substantially longer than the other. Two such elevators 16 are employed in the device herein described. The external edge of the longer parallel faces of the elevator 16 are mitered to present a substantially sharp edge. This longer parallel face is the portion 70 of the elevator that comes in contact with the bottom of the lowest basal plate used in packing the eggs in the case. The area of this plate of the elevator is substantially equal to that of the basal plate used in the packing, so that if the 75

elevator is positioned between the bottom of the case and the lowest basal element, it will raise the basal element, and everything above it in the egg case. In order to move the elevator 16 vertically in the position described, chains 17 are secured or screwed at one end to the shorter parallel plates of the elevator 16, and the other ends of the chains 17 are secured to the shaft 13. Two chains are used for each elevator. All of the chains are the same length. The jointure between the chains and the elevators 16 is made near the lateral edges. The jointure between the chains 17 and the shaft 13 are spaced apart, as best shown in Fig. 4. It will be seen that by the structure thus far described, that when the shaft 13 is rotated that the chains 17 will be wrapped or unwrapped from the shaft 13, depending upon the direction of rotation of the shaft 13. Obviously as the chains are wrapped around the shaft 13, the portion between the shaft 13 and the elevators 16 is shortened.

Prior to placing an egg case in the stand 7, a narrow strip from one of its walls near its bottom is removed, as shown at 18. This permits the insertion of the longer parallel portion of the elevator 16, beneath the lower basal plate.

Numeral 19 designates a rod and numeral 20, channels, which are secured to the inner faces of two of the legs or posts 8. The channels 20 are of the same length. The ends of the rod 19 are in sliding engagement in the channels 20. When the elevator 16 is placed in position, the parallel portions thereof will be in substantial horizontal planes. The chains 17 are of such length that when in their unwrapped position they will be taut, when the elevator 16 is in the position above described. As the shaft 13 is rotated, by means of the handle 14, the elevator 16 moves upwardly vertically, the lower corner of the elevator 16 engaging the rod 19 in frictional engagement. The vertical portion of the elevator 16 in this position moves upwardly in frictional engagement, with the inner faces of the egg case. This engagement between the vertical portion of the elevator 16 and the inner wall of the egg case, prevents the elevator from rotating outwardly and the rod 19 prevents the elevator 16 from rotating inwardly. By these means the upper plate of the elevator 16, in the position indicated, is moved straightly and vertically.

In this movement the rod 19 moves vertically in the channels 20. In order to hold the elevators 16 in any desired position, a pawl and ratchet is employed, the ratchet 21 being secured to the shaft 13 external to the end wall 10. The pawl 22 is rotatively secured to the end wall 10 in operative engagement with the ratchet 21. By the means, thus far described, any and all of the basal plates and separating elements may be moved vertically at will, within the egg case, and so that the upper layer may protrude above the egg case and the stand 7. The egg case may be indicated by the numeral 23, the basal plate by numeral 23' and the separating elements by numeral 24, and the eggs by numeral 25.

Numeral 27 designates a plate or cover, which is secured by hinges 28 to the upper longitudinal wall of the stand 7. The plate 27 may be rotated on the hinges 28 to form a top or cover for the stand 7. It has another and more important function, which will now be described. To perform this function, it must be positioned in a horizontal plane. To accomplish this, the sup-

port 29 is hingedly secured to one of the side walls 9, preferably at one of the posts or legs 8. Numeral 30 designates a transverse cleat secured to the lower side of the plate 27. The support 29 is of such length that when placed in the position, shown in Figs. 2 and 3, the plate 27 will be held in a horizontal position. When the plate is not in use, it may be rotated to its closed position, and the support 29 rotated downwardly to a vertical position, shown in Fig. 3.

Numeral 31 designates a longitudinal stop and 5 32 a transverse stop, both stops being secured to the upper face of the plate 27, when it is in its horizontal position.

Numeral 33 designates a longitudinal slit cut 15 in the plate 27, parallel to and in spaced relationship with the longitudinal stop 31. Numeral 34 20 designates a second slit cut in the plate 27, parallel to the slit 33, and in spaced relationship therewith. The slits 33 and 34 must as a minimum be 20 longer than the longest side of the basal plates, or of the separating elements used in the egg case. The longitudinal stop 31 and the transverse stop 32 are cut away and the slits 33 and 34 extend into the cut away portion.

When it is desired to remove a layer of eggs 25 from the egg case to the plate 27, when the layer is flush with the plate 27, the layer is slid on to the plate 27 against the longitudinal stop 31 and the transverse stop 32. The purpose of this movement is to transfer the eggs, together with the basal plate and separating elements from the egg case to an egg carton. If the egg carton were large enough to accommodate the entire layer of 30 eggs, basal plate and separating elements, no cutting operation would be necessary, but the conventional carton holds one dozen eggs and the conventional layer in the egg case holds three dozen eggs. The carton is shaped so that it will accommodate two rows of eggs, with six eggs in 40 a row, together with the basal plate and separating elements necessary for one dozen eggs so positioned.

Numeral 35 designates a knife, preferably of 45 the type used in cutting bread, which knife may be inserted into the slits 33 and 34 in the plate 27. The knife is used in cutting the basal plates and separating elements. The protruding end edges of the separating plates and the protruding edge of the basal plate must first be trimmed off, 50 so that the two rows of separating elements when cut from the layer will fit into the conventional carton. In order to accomplish this, the distance between the inner edge of the longitudinal stop 31 and the slit 33 is made equal to the width of 55 the protruding edges of the separating elements and the basal plate. When, therefore, the basal plate and separating elements, which are filled with eggs is cornered between the longitudinal stop 31 and the transverse stop 32, the protruding 60 edges of the separating elements and the protruding edge of the basal plate may be cut out by inserting the knife 35 into the slit 33, and cutting or sawing along this line. The knife 35 is then removed, the protruding edges that have been cut 65 off are discarded, and the basal plate, together with the separating elements and their contents are again squared between the longitudinal stop 31 and the transverse stop 32. The distance between the slits 33 and 34 is the same as the width 70 of two egg rows. The knife 35 is then positioned in the slit 34 and the basal plate, together with the separating elements cut. By these means two rows of eggs, 6 to a row, together with the basal plate support, and the separating elements 75

have been separated or cut from the original six row egg layer, together with its basal plate and separating elements.

The next task is to remove the two rows of eggs, 5 together with their supporting basal plate and separating elements from the plate 27 into a carton 36. This is accomplished by holding the carton 36 in the position shown in Fig. 5 in the drawings. In this position one end and the top of 10 the carton is opened, the opposite end of the carton is closed and the side walls stand upwardly. The carton is held so that the inside of the bottom is flush with the top of the plate 27, and so 15 that it registers longitudinally with the two rows of eggs that are to be positioned in the carton. This process is completed by sliding the two rows, together with the basal plate and separating elements through the space between the longitudinal stop 31, and the transverse slot 32, from the 20 plate 27 on to the bottom of the carton 36. When this has been accomplished, the open end of the carton 36 is fastened and the top closed. The removal of the eggs from the case to the carton has, 25 therefore, been accomplished without the handling of the eggs separately; it has been accomplished rapidly and it has permitted the use of the separating elements from the egg case, as the separating elements for the eggs in the carton. Obviously in removing the next carton, no 30 edge of the basal plate, nor separating elements need be cut for removal. The process is continued until three double rows have been cut from the original layer of eggs, and until each double row is lodged in a separate container.

35 In Fig. 6 the elevator 16 is shown for elevating the oranges 37, so that the uppermost oranges will always appear above the top of the case, in which they are packed. Obviously the case always appears to be full of the oranges, as long as 40 there are sufficient oranges within the case to cover one layer of the bottom of the case.

What I claim is:

1. In combination with a stand having a space for the reception of a commodity case, an elevator positioned in said case, said elevator being substantially U-shaped, one of the parallel portions of said elevator being positioned beneath the lowest layer of commodity, filling the commodity case placed in said stand, a rod positioned in sliding engagement in said stand, the other parallel portion of said elevator being placed so 10 that said rod rests in the lower corner of said elevator, a shaft rotatively positioned in said stand, chains having one end secured to said shaft and the other to the lower parallel portion of said elevator, a handle secured to said shaft, 15 a ratchet secured to said shaft, a pawl secured to said stand in operative relationship with said ratchet, so that by rotating said shaft said elevator may be raised or lowered, and so that by means of said pawl and ratchet said elevator may 20 be secured in any of its positions.

2. In combination with a stand having a space for the reception of a commodity case, an elevator positioned in said case, one of the parallel portions of said elevator being positioned beneath 25 the lowest layer of commodity, filling in the commodity case placed in said stand, a rod positioned in sliding engagement in said stand, the other parallel portion of said elevator being placed so that said rod rests in the lower corner of said elevator, a shaft rotatively positioned in said stand, 30 chains having one end secured to said shaft and the other to the lower parallel portion of said elevator, a ratchet secured to said shaft, a pawl secured to said stand in operative relationship with said ratchet, so that by rotating said shaft said elevator may be raised or lowered, and so that by means of said pawl and ratchet said elevator may 35 be secured in any of its positions.

ABNER B. CAREY.
